(57) **CLAIM**

What is claimed is the ornamental design for a suitcase lid with a hatch, as shown and described.

DESCRIPTION

FIG. 1 is a perspective view of a suitcase lid with a hatch according to the present invention;

FIG. 2 is a front view of the suitcase lid according to the present invention;

FIG. 3 is a side view of the suitcase lid according to the present invention;

FIG. 4 is an opposite side view of the suitcase lid according to the present invention; and,

FIG. 5 is a top view of the suitcase lid according to the present invention.

The broken lines depict unclaimed portions of the suitcase lid, which form no part of the claimed design.
